BALL CENTERING AND PROPELLING MECH-
ANISM FOR PLAYING BOARDS

Douglas R. Wiser, Los Angeles, Calif.

Application December 15, 1947, Serial No. 791,774

9 Claims. (Cl. 273—129)

1

This invention relates to gaming devices and more particularly to a new and improved ball-controlling mechanism associated with a new and improved playing board.

In game devices of the general character sometimes known as "pin-ball" machines where the active role of the players consists in the manipulation of a plunger for sending a ball over a designated course or through any of a number of movements depending upon the skill of the operator, considerable attention has been paid to the best mode of construction of the ball-controlling mechanism associated with the plunger.

It has been found particularly desirable to create an improved ball-setting mechanism by which, when the playing ball is released for play, it can be accurately positioned in front of the plunger. In view of the fact that game boards of the character intended vary in construction and, even when of identical construction, have slightly different individual physical and playing characteristics, it is desirable that an accurate positioning mechanism which is readily adjustable, be substituted for the ordinarily rigid and pre-set (and other types known to the prior art) devices.

Sometimes it is desirable to propel the ball for accurate traversal of the playing field in such a manner that the ball rolls slightly to one side of the lane. At other times it is desirable to adjust the effective force of the piston stroke by causing it to impinge against the ball either at an earlier or later point in its movement.

It is particularly desirable in devices of this character that the degree of tension applied to the plunger should be capable of easy and obvious adjustment. In part this is desirable because of the necessity of pre-setting any machine in a number of playing units engaged in competitive play so that all will operate in substantially the same manner. At other times, either due to wear, temperature, desires of individual players, or other indeterminate conditions, it becomes necessary to rapidly and accurately adjust the tension of the spring or similar plunger-actuating means.

Moreover, it is desirable that all operative parts of the plunger mechanism or the apparatus associated therewith be readily removable for replacement or repair.

It is therefore an object of this playing board to provide a smoothly operable and readily adjustable ball-control means in order to achieve the desired results above referred to.

2

It is another object of this invention to provide a new and improved ball-holding mechanism having a new and improved relationship with the plunger and the ball.

Another object of the invention is to provide a new and improved ball for use with the desired form of the apparatus described.

Another object of the invention is the provision of a new and improved plunger-actuating means.

Another object of the invention is the provision of a new and improved ball-positioning device having a new and improved association with the plunger means.

Still another object of the invention is the provision, by incorporation of the above and other elements, of a new and improved playing board.

Still another object of the invention is the provision of a new and improved ball stop or lock.

Another further object of the invention is to provide a ball-control mechanism of the desired character which may be economically manufactured and assembled, which has a maximum use facility, which is stable and consistent in operation, which will not become loosened or inoperative during ordinary play and, which when adjustment proves necessary, can be restored with a minimum expenditure of time and effort.

Another and still further important object of the invention is to provide a new and improved plunger and ball-impelling mechanism of such a simple operating principle and construction that its entire mode of operation is readily seen and understood by any interested or otherwise skeptical player.

The invention also has among its objects the improvement of like devices heretofore utilized in the prior art to accomplish a generally similar purpose.

Other objects and purposes of this invention will become more apparent from the following description and claims considered in the light of the accompanying drawings.

In the drawings:

Figure 1 is a perspective view of an improved playing board embodying this invention (parts being cut away).

Figure 2 is a plan view of the playing board.

Figure 3 is a detailed sectional view taken as on a line 3—3 of Figure 2.

Figure 4 is a detailed sectional view taken as on a line 4—4 of Figure 2.

Figure 5 is a fragmentary detailed plan view (parts being cut away) as illustrated at the lower right-hand corner of Figure 2.

Figure 6 is a view similar to Figure 5 showing the parts in a different operative relationship.

Referring more particularly to the drawings, a playing unit generally designated by the numeral 20 preferably comprises a playing board 21. A portion of the board or field in front of the plunger mechanism generally designated at 23, may include a lane 24 optionally marked off and separated from the remainder of the playing field as by a wire guard 25. The opposite side of the lane 24 may be defined as by the curved wall 26, usually terminating in a bumper or rebound surface 27. The central portion of the playing field may be divided into any number of passageways as 28, 29, 30, 31, 32, and 33 having therein any number of light contacts, bell-ringers or the like 34 of any conventional construction. Likewise, any number of indicator lamps 35 or the like may be connected in any desired combination with the buttons 34.

Other wire guards as 36 and 37 may guide a preferably rubber ball 38 across the sloping playing field 21 back to a point of rest in front of the plunger mechanism 23, as will be described.

Also, as is customary in playing units of this character, the playing field may be equipped with a cover of glass or the like 40 as shown fragmentally in Figures 1 and 2.

The plunger mechanism itself heretofore generally designated at 23, preferably comprises a plunger rod 50 slideably positioned within an opening 51 in the front side 52 of the playing unit. The plunger is additionally slideable as within a plunger guide 53 of conventional construction secured in any desired manner to the surface of the front side 52. At its near end the plunger may be fitted with any appropriately formed handle 54 and, preferably adjacent its ball-engaging end 56, may be fitted with an annular collar 57 optionally formed integral therewith, sweated thereto, or loosely disposed thereon and held in place as by a pin (not shown), annular recess (not shown), or other well-known construction. Obviously, if desired, the shoulder 57 need not be annular in shape but may comprise any suitable abutment formed in or connected to the plunger rod 50 for a purpose to be described.

Any suitable yoke such as a staple 60 may be secured in the upper face of the playing field 21 preferably to one side of the axis of the plunger rod. An arm 61 may be formed with parallel sides 62 and 63 connected together at one end 64 and formed with corresponding arcuate edges 65 and 66 respectively at its other end 67. Said arm 61 may obviously be formed of separate pieces joined together at the end 64 or at any point between the end 64 and the end 67. It is sometimes preferable, however, that the end 67 be bifurcate in order that it may straddle the plunger rod 50 to distribute the pressure of a coil spring 70 or the like. The arm 61, as to both of its sides 62 and 63, may be formed with a notch or detent 71. Such notch is intended to serve as a pintle and to turn or hinge upon one side 74 of the yoke 60.

It is expressly not intended to exclude from the spirit or ambit of this invention the use of a simple arm 61 without a bifurcation, nor the use of a slotted plunger to receive such arm although players prefer that the plunger rod itself be freely twistable or rotatable. It may therefore also be formed of a single piece and may engage the annular shoulder 57 or any other form of shoulder or abutment on only one side of the plunger 50. Manifestly also, the arm 61 while

preferably provided with an adjustable spring 70 as illustrated, may be provided with any other form of spring and the spring so provided need not necessarily be secured to the arm 61 between the yoke 60 and the end 67, but may instead have its effective force applied in an opposite direction as, for example, by its attachment to the end 64. Indeed, the arm 61 may be of any desired shape, either straight or curved, and may if such construction is preferred, be formed of any number of links. It may also be secured firmly, i. e. pivotally, to the plunger 50 as by means of a pin or the like, in which case the detent 71 may obviously be omitted so that the arm 61 is free to slide through the yoke 60 upon pivotal movement of the end 67. Many such simplifications or modifications will readily occur to anyone skilled in the art of mechanics.

The coil spring 70 may be secured to the arm 61 as through an opening 75 into which an end 76 of the coil spring may be inserted or tied. The other end 77 of the coil spring is preferably secured to an adjustable eye bolt or the like 78. The shank 79 of the eye bolt is preferably loosely confined within and extends through any appropriate member or loop such as may be formed by an eyelet 80 secured to the playing field 21. Thus, the amount of tension of the coil spring 70 may be obviously and readily adjusted by threading a nut 81 thereon. If desired, said nut may be a wing-type for convenient adjustment by an operator or player or it may be associated with a jam or lock nut (not shown) to retain the same in a selected position. In practice, however, this expedient has not proven necessary or even desirable.

Associated with the end 56 of the plunger, and optionally of the simple wire form shown, a ball-positioning device 85 may comprise a substantially W-shaped structure, including a pair of upturned points or ends 83 and 84. The central portion of the positioning device may comprise substantially parallel legs 86 defining a slot 87 therebetween through which a bolt 90 may extend to secure the device in any desired degree of relative angularity with or proximity to the end 56 of the plunger rod. That is to say, by loosening the bolt 90 from its threaded securing in the playing field 21, the positioning device 85 may be moved about so that the points 83 and 84 can engage and hold the ball 38 in any desired position to move or adjust the same along or from side to side with respect to the end 56.

As a further element in the control of the ball on the playing unit, a stop 95 may be formed with an upper leg 96 which may be swung into the path of the ball as upon a vertical or pivot leg 97 pivotally and slideably confined within a plate 98 secured to the playing field for such purpose. Another horizontal leg 99 may form an armature for a coil 100. Upon the actuation of the coil the leg 99 is attracted, thereby swinging the arm 96 into a position most clearly illustrated in Figure 6 wherein the ball 38 is held away from the end 56 of the plunger in the most advanced position of the latter. The coil 100 may be energized by a battery 101 connected with the coil as by conductors 102 and 103. A switch 104 may be used either manually or automatically to close a circuit between the battery 101 and the coil 100 at any desired point in the game.

This invention features the provision of a new and improved ball-regulating mechanism and in particular a new and improved accurate plunger-impelling mechanism of simple, readily under-

stood, readily observable, and easily adjustable construction.

The respective parts of the mechanism may be made of any desired material such as wood, metal, or plastic although it is preferred that the spring, such as 70, be of conventional spring steel, and it has been found particularly entertaining to use a ball of rubber or like resilient construction, whether hollow or solid, since thereby any amount of "english" or spin may be given it to change or vary the manner of play depending upon the adjustment of the holding mechanism and the plunger tension.

Mode of operation

The mode of operation of the instant invention is believed readily apparent. When a player desires to cause the ball 38 to roll over the playing field, he retracts the plunger 50 by means of the handle 54 against the tension of the coil spring 70 which has been adjusted to a desired extent by threading the nut 81 upon the bolt 79. The arm 61 thereby bears against the shoulder 57 and, when the plunger handle 54 is released, drives the plunger 50 forwardly to impinge against the ball 38, driving the same with any desired amount of impetus and at any angle along the lane 24 and over the playing board, whence, due to the inclination of the board, it is returned as by the several guides 25, 36, and 37 to said position in front of the plunger as illustrated, for example, in dotted outline in Figure 2. From said position it can be replayed.

Inasmuch as it is usually desirable that the ball 38 be driven accurately along the lane 24, the relative alignment of the plunger and the ball is achieved for such purpose by means of the positioning device 65 whose points 83 and 84, engaging the ball at spaced points, are subject to securing in a desired position by the bolt 90.

Upon the completion of a usually predetermined number of plays, or otherwise at the conclusion of a game, an operator may close the switch 104 thereby energizing the coil 100 and attracting a portion 99 comprising the armature of the ball stop so as to carry the end 95 around and engage the ball, holding the same away from the end 56 of the plunger to prevent further play. To return the ball stop and release the ball, upon de-energization of the coil, a spring or the like (not shown) may be employed.

Although the invention has been herein shown and described in what is conceived to be the most practical and preferred embodiment, it is recognized that departures may be made therefrom within the scope of the invention which is not to be limited to the details disclosed herein but is to be accorded the full scope of the claims so as to embrace any and all equivalent structures.

The invention having been herein described, what I claim as new and desire to secure by Letters Patent is:

1. In a playing unit having a field and a lane for a ball to be played, a ball centering and propelling mechanism comprising: a plunger extensible into said lane for playing said ball, pusher means operatively associated with the plunger to urge the same to one extreme of axial movement, adjustable means including a threaded finger-piece for regulating the tension of said pusher means, said pusher means comprising a single pivotal element disposed transversely of said plunger, and stationary adjustable ball-positioning means in the lane for cen-

tering a ball to be propelled by the plunger relative to said plunger.

2. In a playing unit having a field and a lane for a ball to be played, a ball centering and propelling mechanism comprising: a plunger extensible into said lane for playing said ball, pusher means operatively associated with the plunger to urge the same to one extreme of axial movement, adjustable means including a threaded finger-piece for regulating the tension of said pusher means, said pusher means comprising a single pivotal element disposed transversely of said plunger, and adjustable ball positioning means in the lane for centering a ball to be propelled by the plunger relative to said plunger, said last named means comprising a forked member secured to the unit, engageable with the ball and adjustable relative to the plunger, whereby the effective direction and force applied to the ball may be regulated.

3. In a playing unit having a field and a lane for a ball to be played, a ball centering and propelling mechanism comprising: a plunger extensible into said lane for playing said ball, pusher means operatively associated with the plunger to urge the same to one extreme of axial movement, adjustable means including a threaded finger-piece for regulating the tension of said pusher means, said pusher means comprising a pivotal element disposed transversely of said plunger, means in the lane comprising a substantially W-shaped member adjustably mounted in the lane to provide engagement between the ball and plunger, said member having elevated ends secured to the unit by means of a central portion of said member, said ends being engageable with the ball and adjustable relative to the plunger, whereby the effective direction and force applied to the ball may be regulated, and stop means for holding said ball relative to said ends and the plunger to prevent play.

4. In a ball centering and propelling mechanism for a playing board utilizing a plunger, an abutment on the plunger, a yoke secured to the playing board at a point spaced from the plunger, a member free to pivot within the yoke and having an arcuate portion engageable with the abutment, and adjustable spring means secured to the board and connected with said member to regulate the tension of the plunger, said member comprising a bifurcate arm normally bearing against said abutment at opposite sides of said plunger, and said member including a detent forming a pintle element engageable with the yoke to permit relative rotation but prevent relative lineal movement thereof.

5. In a ball centering and propelling mechanism for a playing board utilizing a plunger, an abutment on the plunger, a yoke secured to the playing board at a point spaced from the plunger, a member free to pivot within the yoke and having an arcuate portion engageable with the abutment, and adjustable spring means secured to the board and connected with said member to regulate the tension of the plunger, said member including a detent forming a pintle element engageable with the yoke to permit relative rotation but prevent relative lineal movement thereof and said member normally bearing against said yoke at spaced points relative to the surface of said playing board.

6. In a playing unit having a field and a lane for a ball to be played, a ball centering and propelling mechanism comprising: a plunger extensible into said lane for playing said ball, an

abutment on said plunger, an arm normally engaging said abutment, a pivot for said arm spaced laterally from said plunger, and a spring secured to said arm and to said unit at a point spaced from the pivot and abutment, normally urging said arm pivotally against said abutment for urging said plunger to a limit of extension, said spring secured to said unit comprising a screw-eye, a threaded extension on the spring extending through the screw-eye, and threaded means on said extension for adjusting the tension of the spring.

7. In a playing unit having a field and a lane for a ball to be played, a ball centering and propelling mechanism comprising: a plunger extensible into said lane for playing said ball, pusher means operatively associated with the plunger to urge the same to one extreme of axial movement, adjustable means for selectively regulating the tension of said pusher means, said pusher means comprising a pivotal element disposed transversely of said plunger, a spring secured to said element, a ball to be played by said plunger, and means in the lane adjacent the front end of the plunger comprising a substantially W-shaped member having elevated ends secured to the unit by means of the open, notch-like central portion of said member, said ends being engageable with the ball, a screw threadable into the unit, a head on the screw engageable with the edges of said notch portion whereby the member may be moved axially forward, or angularly fixedly held in any adjusted relationship to the plunger, to regulate the effective direction and force applied to the ball by the plunger.

8. In a ball centering and propelling mechanism for a playing board utilizing a plunger having a finger piece at one end for direct manipulation, an abutment on the plunger, a yoke secured to the playing board at a point spaced from the plunger, a member free to pivot within the yoke

and having a portion engageable with the abutment, and adjustable spring-secured means between said member and the playing board to regulate the tension of the plunger and to urge said pivotal movement of said member against said abutment to drive the plunger freely forward when drawn back and released.

9. In a ball centering and propelling mechanism for a playing board utilizing a plunger having a finger piece at one end for direct manipulation thereof, an abutment on the plunger, a pivot means secured to the playing board at a point laterally spaced from the plunger, a lever member free to turn on the pivot means and having a portion engageable with said abutment, and adjustable springs means secured between said member and the playing board to regulate the tension of the plunger and to turn said member on said pivot and to force said portion against said abutment to drive the plunger freely forward when the same is operatively drawn back and released.
